CATHODE-RAY DEVICE

Cyrus H. Babbs, Cambridge, England, assignor to
Pye Limited, Cambridge, England, a British
company

Application February 25, 1947, Serial No. 730,719
In Great Britain March 2, 1946

6 Claims. (Cl. 250—157)

1

The present invention relates to cathode ray devices, such as cathode ray tubes, monoscopes and electron pickup tubes as used in television, in which the cathode ray beam is focussed and deflected by electromagnetic means, such as by coils disposed around the neck of the tube.

In such devices the deflecting coils and/or the cathode ray gun may introduce astigmatism by distorting the electron beam, and the present invention has for its object to provide additional means which introduce astigmatism of the cathode ray beam to compensate for the astigmatism produced by the deflecting coils and/or the cathode ray gun.

According to the present invention, two magnetic members are disposed at diametrically opposite positions with respect to the axis of the cathode ray gun and between the focussing coil and the gun. The magnetic members are carried by a non-magnetic framework or ring which is adjustable both rotatably and longitudinally.

In order that the invention may be more clearly understood, reference will now be made to the accompanying drawings, in which:

Fig. 1 shows a plan view, partly cut away, of a cathode ray tube incorporating the compensating device according to this invention.

Fig. 2 shows a perspective view of the compensating device.

Referring to the drawings, the neck portion of the cathode ray tube 1 having the electron gun 2 disposed at its end is surrounded by the focussing coil 3 and deflecting coils 4 in known manner. According to the invention two soft iron pins 5 and 6 are supported at diametrically opposite points of the neck of the tube and between the focussing coil 3 and the gun 2 by means of a ring 7 of non-magnetic material. In the embodiment shown the ring 7 is constructed in the form of a tubular member which is provided with a longitudinal slit 8 to impart slight resiliency to this member and allow it to bear with friction upon the outer surface of the neck portion of the cathode ray tube. At the end of the tubular member 7 is provided a collar 9, which preferably has a knurled peripheral edge, by means of which the tubular member and the two soft iron pins carried thereby can be adjusted longitudinally along the neck of the tube and rotatably therearound. The iron pins 5 and 6 are disposed with their axes extending in the direction of the longitudinal axis of the tube.

By adjusting the position of the iron pins, both longitudinally and rotatably with respect to the focussing coil, astigmatism can be introduced

5 into the focussing which is such that it compensates for the astigmatism caused by deflecting coil de-focussing and/or by the cathode ray gun. The compensating device is adjusted with the scanning voltages applied on the deflecting coils to produce the sharpest definition of the electron beam.

Whilst a particular embodiment has been described, it will be understood that various modifications may be made without departing from the scope of the invention as defined by the appended claims.

I claim:

1. A cathode ray device comprising an evacuated envelope having a neck portion containing an electron gun, magnetic focussing means and electro-magnetic deflecting coils surrounding said neck portion, a non-magnetic member adjustable longitudinally with respect to the axis of the gun, 10 two magnetisable members mounted on said non-magnetic member in diametrically opposed portions with respect to the axis of the gun, said magnetisable members being disposed in the magnetic field of the focussing means for magnetisation thereby.

2. A cathode ray device comprising an evacuated envelope having a neck portion containing an electron gun, magnetic focussing means and electro-magnetic deflecting coils surrounding said neck portion, a non-magnetic member adjustable both rotatably and longitudinally with respect to the axis of the gun, 20 two magnetisable members mounted on said non-magnetic member in diametrically opposed positions with respect to the axis of the gun, said magnetisable members being disposed in the magnetic field of the focussing means for magnetisation thereby.

3. A cathode ray device comprising an evacuated envelope having a neck portion containing an electron gun, magnetic focussing means and electro-magnetic deflecting coils surrounding said neck portion, a non-magnetic member adjustable longitudinally with respect to the axis of the gun, 30 two soft iron pins disposed with their axes extending in the direction of the axis of the gun mounted on said non-magnetic member in diametrically opposed positions with respect to the axis of the gun, said soft iron pins being disposed in the magnetic field of the focussing means for magnetisation thereby.

4. A cathode ray device comprising an evacuated envelope having a neck portion containing an electron gun, magnetic focussing means and electro-magnetic deflecting coils surrounding said neck portion, a split tubular member of non-

magnetic material adjustable at least longitudinally with respect to the axis of the gun, two soft iron pins disposed with their axes extending in the direction of the axis of the gun mounted on said non-magnetic member in diametrically opposed positions with respect to the axis of the gun, said magnetisable members being disposed in the magnetic field of the focussing means for magnetisation thereby, the intensity of magnetisation being adjustable by longitudinal movement of the non-magnetic member relatively to the focussing means.

5. A cathode ray device comprising an evacuated envelope having a neck portion containing an electron gun, magnetic focussing means and electro-magnetic deflecting coils surrounding said neck portion, a split tubular member of non-magnetic material having a collar to facilitate manual adjustment of the non-magnetic member both rotatably and longitudinally with respect to the axis of the gun, two soft iron pins disposed with their axes extending in the direction of the axis of the gun mounted on said non-magnetic member in diametrically opposed positions with respect to the axis of the gun, said magnetisable members being disposed in the magnetic field of the focussing means for magnetisation thereby, the intensity of magnetisation being adjustable by longitudinal movement of the non-magnetic member relatively to the focussing means.

30

6. A cathode ray device comprising an evacuated envelope having a neck portion containing an electron gun, an electro-magnetic focussing coil and electro-magnetic deflecting coils surrounding said neck portion, two pins of magnetisable material disposed substantially parallel to and at the diametrically opposed positions with respect to the axis of said gun, a non-magnetic member carrying said pins, said carrying member being movable longitudinally with respect to the focussing coil to adjust the intensity of magnetisation of the pins by the magnetic field of the focussing coil, said carrying member also being rotatable with respect to the axis of the gun, to adjust the rotational position of said pins.
